(57) **CLAIM**

The ornamental design for a hood fender, as shown and described.

DESCRIPTION

FIG. 1 is a perspective view of a hood fender according to our new design;

FIG. 2 is a left side elevational view of the hood fender of FIG. 1;

FIG. 3 is a top plan view of the hood fender of FIG. 1; FIG. 4 is a front elevational view of the hood fender of FIG. 1; and,

FIG. 5 is a rear elevational view of the hood fender of FIG. 1. The right side of the hood fender is unornamented.

FIGS. 1-5 illustrate a first embodiment of our novel design suitable for use on the left side of a vehicle. Our novel design also includes a second embodiment suitable for use on the right side of a vehicle, which is mirrored symmetrical to FIGS. 1-5 and therefore not separately illustrated.

The broken lines shown in the drawings illustrate portions of the hood fender that form no part of the claimed design.
